[57] ABSTRACT

The invention relates to a miniaturized YIG band-pass filter with first poles for achieving high selectivity in the microwave range, in which the coupling structure consists of, for example, crossed coaxial inner conductors in an external magnet circuit which are semicircularly bent over the YIG elements, the coupling structure for the YIG resonators being arranged in a filter body which is made of, for example, copper or brass, such that the coaxial supply conductors for coupling the YIG resonators are adjacently arranged and are magnetically coupled, i.e., in the case of filters comprising an even number of YIG resonators they are coupled to each other, and in the case of filters comprising an odd number of YIG resonators the first and the last supply conductor are coupled. The magnetic coupling between the supply conductors can be varied by means of a displaceable shutter.

MINIATURIZED YIG BAND-PASS FILTER HAVING DEFINED DAMPING POLES

The invention relates to a miniaturized YIG band-pass filter, comprising damping poles in order to achieve high selectivity in the microwave range, in which the coupling structure includes crossed coaxial inner conductors in an external magnetic circuit which are semicircularly bent over the YIG element.

Use is made of the ferrimagnetic resonance in ferrite bodies; use is preferably made of yttrium-iron-garnet or similar YIG monocrystals, for example, substituted with Ga, which have very small resonance line widths and hence high resonance qualities. As in the first instance the resonant frequency of the ferrimagnetic resonance is determined only by the strength of a static or quasi-static magnetizing field, the absolute dimensions of the ferrimagnetic resonator — as opposed to conventional microwave filters with line or cavity resonators — are of no importance in the first instance; use is preferably made of polished balls having typical diameters of between 0.3 and 1 mm. This property of the YIG resonators can be used to good advantage so as to realize very small filters; in particular, very small permanently tuned or mechanically tunable filters can be manufactured by means of permanent magnets. These properties are particularly important for the miniaturized microwave circuits in the strip conductor technique (microstrip) which are manufactured by photo-etching and which are being applied in increasing numbers. Strip conductor substrates are generally made of ceramic and have a dielectric constant ϵ of between 9 and 16. Consequently, a reduction of $\sqrt{\epsilon}$ is produced, i.e., approximately a factor 3 – 4; moreover, ignoring the substrate thickness of between 0.2 and 0.6 mm, the strip conductor circuits are only two-dimensional. Due to the comparatively high conduction losses in strip conductors, conventional line resonators in this technique have low, unloaded qualities in the order of magnetic between 100 and 400 (YIG resonators 1,000 – 10,000). Since the losses of a band-pass filter are inversely proportional to the bandwidth and the unloaded quality, narrow band filters having low losses and high selectivity cannot be realized according to the strip conductor technique. A desired interconnection of known low-loss coaxial circuit filters or cavity filters and strip conductor circuits is seldom feasible particularly due to their various dimensions. On the other hand, YIG filters can in principle be realized with structural dimensions which are compatible with the strip conductor technique.

The invention had for its object to provide, by means of YIG resonators, low-loss, narrow band bandpass filters of small volume which can be readily incorporated in a microstrip circuit without taking in too much space, and having defined damping poles and a very large slope steepness of their characteristic curve.

It must be possible for the filter to be inserted in a strip conductor circuit as a complete structural component similar to, for example, diodes or transistors.

As is known, the slope steepness of a filter (selectively) increases as the number of resonant circuits used increases. In the case of a given number of resonant circuits, methods are also known how to produce defined damping poles on the filter curve to increase the slope steepness (known methods: Zobel elements, Cauer elements, elliptically coupled filters, n-path fil-

ters). The use of this technique reduces the number of resonant circuits required for a given damping of a filter, thus offering substantial savings as regards money and structural dimensions. For example, a two-circuit band-pass filter with two damping poles can have a slope steepness which corresponds to that of a three or four-circuit straight-coupling filter (Tchebyscheff, Butterworth), and the losses in the band-pass range are even smaller. These filters are particularly suitable if

10 the image frequency of the desired intermediate frequency is to be suppressed in an RF mixer the distance between the band-pass centre frequency and the pole frequency must then be equal to twice the intermediate frequency.

15 According to the invention a band-pass filter with two well defined damping poles of its characteristic curve is achieved in that the coupling structure for the YIG resonators in a filter body which is made of, for example, copper or brass, is arranged such that the coaxial supply conductors for coupling the first and for coupling the last YIG resonator are adjacently arranged and are magnetically coupled to each other in filters comprising an even number of YIG resonators or, in the case of filters comprising an odd number of YIG

20 resonators, the coaxial supply conductor for coupling the first YIG resonator is magnetically coupled to the conductor for coupling the last YIG resonator.

25 The drawing shows some embodiments according to the invention. Therein:

30 FIG. 1 shows in cross-section a two-stage YIG band-pass filter component,

FIG. 2 is a perspective view of the embodiment of FIG. 1 comprising magnets,

FIG. 3 is a diagrammatic plan view of the embodiment of FIG. 1,

FIG. 4 shows band-pass filter curves,

FIG. 5 shows a cross-section through a YIG filter with magnetic coupling,

FIG. 6 is a diagrammatic plan view of the embodiment of FIG. 5,

FIG. 7 is a cross-sectional view of a further embodiment, and

FIG. 8 is a diagrammatic view of a tunable embodiment with magnets.

45 In accordance with FIG. 1, the coaxial inner conductor 2 for the supply are fed out of the filter block 1 such that they are adjacently arranged, preferably in parallel, at a distance of approximately 0.5 to 1 mm from each other. The filter body which is mounted in a permanent magnet is first built into a measuring adapter and the YIG balls 3 are adjusted according to the frequency wobbling method by means of holders 3'. The filter component thus obtained is connected to the strip conductor circuit supported on a substrate 5 which is provided with a grounded plate 9 and appropriate passage holes. The connection is made by soldering or by bonding the coaxial inner conductor which is fed out of the filter component to the ends of the strip conductor 8 which are provided for this purpose. FIG. 1 shows an embodiment for a two-stage miniaturized YIG band-pass filter component; the magnet which is omitted in FIG. 1, is shown in FIG. 2. FIG. 1 further illustrates inner coupling conductor 2', crossed semicircular coupling loops 4, fixing leaf spring 6, and screw 7. FIG. 2

50 55 60 65 65 is a perspective view of the filter component with magnets, in this case a permanent magnet circuit, comprising a yoke 10 and permanent magnets 11. The connec-

tion of the magnet to the filter body can be effected by screwing, or by bonding or soldering. A method of connecting the filter component in a strip conductor substrate is shown in FIG. 3: the fixing spring 6 is screwed to a projection 15 of the filter body 1 by means of a screw 7, the spring 6 then pressing 6 then pressing on the substrate (FIG. 3), thus producing a counter pressure. The coaxial supply conductors 2 can be connected in a conductive manner to the strip conductor 8 by soldering or bonding.

To produce damping poles in the filter curve, the supply conductors 2 which are magnetically coupled to the YIG resonators are also coupled to each other. The principle will be described with reference to FIG. 4. The transmission curve 12 which is denoted by a signal passing through a broken line represents the amplitude behaviour of a straight-coupled band-pass filter, as a function of the frequency; line 13 shows the transmission α_k introduced by the magnetic coupling of the supply conductors (which can be measured, for example, when the YIG balls are removed from the filter body). Curve 14 is a resulting band-pass filter curve with damping poles. The pole frequencies f_1 and f_2 are situated at the intersections of lines 12 and 13 (interference); at these intersections the signal transmitted by the YIG resonators and the signal (α_k) transmitted by the magnetic coupling of the supply conductors cancel each other. It was experimentally found that the damping poles are situated between 65 dB and 70 dB, determined by minor phase errors, so that the condition of equal amplitudes in the case of opposed phase does not occur simultaneously. By changing the level α_k of the directly coupled signal, the distance from the pole frequencies f_1 and f_2 to the centre frequency f_0 can be symmetrically shifted; starting from the 3 dB band width (Δf_3 dB) of the filter, values ($f_0 - f_1$) of approximately $3\Delta f_3$ dB to $10\Delta f_3$ dB can be achieved, which corresponds to a coupling level α_k of -30 dB to approximately 55 dB.

The interference required for producing the damping poles can occur symmetrically on both filter flanks only if the signal frequencies f ($f \geq f_0$), transmitted by the filter and situated about f_0 below and above the pass frequency range, have approximately the same phase or a phase position which is shifted a multiple of 2π with respect to each other. In band-pass filters the phase position for signals $f \geq f_0$ generally amounts to a multiple of π which is about equal to the number of filter circuits: the above phase condition (multiple of 2π) is satisfied only if there is an even number of filter circuits; in that case the magnetic coupling α_k between the filter supply conductors can be effected as described in the foregoing.

In the case of an odd number of filter circuits, the magnetic coupling α_k must be effected, for example, between the supply conductor for the (external) coupling of the first resonator and the inner coupling conductor 2' for the (inner, related to the filter) coupling of the last resonator.

The magnetic coupling of the supply conductors can be effected through partial opening of the partition between the supply conductors. FIGS. 5 and 6 show an embodiment which results from the omission of the bar 15. The distance a between the filter supply conductors 2 as well as the distance b between the filter bodies and the conductor side of the microstrip substrate influence the level α_k of the directly coupled signal. FIG. 7 shows

the principle of an embodiment which enables continuous adjustment of the coupling level α_k , the two supply conductors being coupled through the slit 16; the coupling can be varied by means of a displaceable shutter 17. Other similar devices utilizing screws are alternatively possible.

FIGS. 6 and 8 show a further method of connecting the filter body to the microstrip substrate. The filter which is arranged below the substrate is secured by means of the screws 18 on the circuit side of the substrate. FIG. 8 shows the required threaded holes 19, for example, in the magnet yoke. FIG. 8 also shows a simple possibility of tuning the centre frequency of the filter by screwing the screw 20, made of a magnetic material, further into or out of the hole so that a magnetic shunt is produced which more or less decreases the field in the range of the filter, and hence the resonant frequency. By means of a coil 21 in the magnetic circuit, an electronic (additional) tuning can also be achieved which is advantageous, for example, for an electronically controlled frequency readjustment. The generation of pole frequencies is not restricted to the special cases described here, but the required measures can also be realized in known electronically tunable YIG filters in accordance with the described embodiments.

Finally, some results will be given which were obtained on an embodiment according to FIG. 6 (and FIG. 8):

Centre frequency f_0 — 2,500 MHz

Intermediate damping — 1.5 dB

3 dB bandwidth — 12 MHz

Pole frequencies — $f_0 \pm 60$ MHz

Pole damping — 67 dB

Coupling level α_k — -47 dB

Dimensions of the filter block — $12 \times 6 \times 5$ mm³

Mechanical tuning range — 2,500 — 2,000 MHz

Temperature-dependency of f_0 — approximately 20 KHz/°C.

What is claimed is:

1. A miniaturized YIG band-pass filter having defined damping poles comprising: an even number of ferrimagnetic YIG resonators, a filter body of electro-conductive non-magnetizable material, a corresponding number of chambers formed in said body for receiving said YIG resonators, respectively, the first and the last chamber being arranged adjacent each other and interconnected by a coupling aperture, two parallel passages leading from said first and last chambers respectively, to an external surface of said body, an input and output coupling structure including coaxial supply conductors passing through said passages and being magnetically coupled to one side of said YIG elements, a crossed inner conductor passing through said coupling aperture and being magnetically coupled to another side of said YIG elements, and an open space formed in said body between predetermined portions of said supply conductor to produce an additional coupling therebetween thereby forming damping poles in the filter curve.

2. A YIG bandpass filter as claimed in claim 1, characterized in that an adjustable magnetic shunt is provided for the external magnetic field for the YIG resonators.

3. A YIG band-pass filter as claimed in claim 1, characterized in that the external magnetic circuit can be electronically adjusted by means of a coil.

4. A YIG band-pass filter as claimed in claim 1 characterized in that the open space is an opening in the partition between the passages for the coaxial supply conductors.

5. A YIG band-pass filter as claimed in claim 4, characterized in that the open space between the supply conductors is adjustable by means of a displaceable shutter.

6. A band-pass filter according to claim 4, further including an additional chamber with a YIG resonator, and portions of said crossed inner conductor being directed against side opening to introduce coupling between a supply conductor of one YIG resonator and the inner conductor near the other YIG resonator.
